UNITED STATES PATENT OFFICE.

CHARLES NATHAN JOHNSON, OF CHICAGO, ILLINOIS.

WINDOW WEIGHT.

1,402,865.

Specification of Letters Patent. Patented Jan. 10, 1922.

Application filed April 8, 1921. Serial No. 459,627.

To all whom it may concern:

Be it known that I, CHARLES NATHAN JOHNSON, a citizen of the United States of America, and a resident of Chicago, county 5 of Cook, and State of Illinois, have invented certain new and useful Improvements in Window Weights, of which the following is a specification.

This invention relates to counterpoise devices and especially to sash-weights for windows.

The main objects of the invention are to provide a counterpoise of improved composition, structure, and form; to provide an improved method of manufacturing and assembling the parts of such devices into units ready for use; to provide sash-weights of knock-down sectional character adapted for ready assemblage of its parts, and with any desired number of sections hung in vertical alinement, so as to facilitate ready adjustment according to the weight of the sash to be balanced; and to provide a form of counterpoise structure and method of commercial distribution and fabrication which will permit independent manufacture and shipping of its several parts to the point of retail or use, where said parts may be put together by unskilled labor ready for use 30 in the window casing.

An illustrative embodiment of this invention is shown in the accompanying drawings, in which—

Figure 1 is a perspective view of one corner of a window-casing with part broken away to show the sash-weight and cord on one side of the window.

Fig. 2 is an enlarged side view of a one-brick sash-weight with an interchangeable 40 "stringing" rod.

Fig. 3 is an edgewise view of the upper end of the device of Fig. 2.

Fig. 4 is a plan of the sheet metal punching from which the pulley frame is made.

Fig. 5 is a section on the line 5—5 of Fig. 2 and shows an end view of the "brick" or weight proper.

Fig. 6 is a side view of a four-section multiple brick counterpoise, similar to Fig. 2 except as to the number and size of bricks.

Fig. 7 is a side view of a stringing rod which, if desired may be cut off at any one of several points according to the number of weight sections to be used in any specific instances, said sections being indicated by dotted lines.

Fig. 8 shows an assortment of rods adapted for two, three and four full-sized blocks respectively.

In the construction shown in the drawings the window casing 1 is provided with a lower sash 2 and an upper sash 3. A single sash weight 4 is provided on each side of the casing as will be understood, each of said weights being supported by a window 60 cord 5 running on a pair of stationary sash pulleys 6 and 7 journaled in alinement in the upper part of the casing and corresponding with the sashes 2 and 3 respectively.

The counterpoise 4 is provided with an equalizing pulley 8 which receives the cord 5 and thereby renders the weight effective for balancing both sashes.

In order that the counterpoise may be adjustable to accommodate window sashes of different sizes, the member 4 is made in sections 9 adapted for stringing together in series as on a rod 10. The wheel of pulley 8 is pivoted at 11 in a frame 12 which in turn 70 is pinned at 13 to the upper end of the rod 10. The rod itself is secured to a weight 4 by means of a cotter-pin or the like as shown at 14.

Each weight section 9 is made in the form 85 of a concrete block of rectangular shape and provided with a longitudinal axial perforation 9' having a cross section corresponding with the shape of the rod 10 whereby relative turning of the rod in the sections is prevented.

The rods 10 may be made up in various lengths adapted to support weights comprising one, two, three or more sections respectively, as may be required in any instance, 95 or the rods may be made up long enough to accommodate a maximum number of sections and provided with perforations 15 so located that the rod may be cut as at points 16 to proper length to accommodate any desired number of sections and the holes being arranged to properly position the necessary retaining pin as illustrated in Figs. 6 and 7.

The frame 12 for pulley 8 is preferably made in the form of a sheet metal punching 17, the stamping for which is of substantially the shape shown in Fig. 4. In order to form this punching into the shape shown in Fig. 2, connecting part 18 is bent into a U-shape as by bending on the lines 19, and 100 the T-ends 20 are bent inwardly at their tips 21 as by bending on the lines 22. In

punching this member holes are provided at 23 to receive the pulley pintle 11 and at 24 to receive the rod pintle 13. A rectangular hole 25 is also punched in the middle of part 5 18 to receive the upper end of rod 10.

- The blocks 9 are formed of concrete composed of a dense mineral matter, preferably slag, which has been ground and mixed with a suitable binder and water. This matter 10 is molded into blocks by means of presses as understood in the art. In molding the blocks the central perforation is provided by means of a core which is withdrawn when the block is removed from the mold, 15 the details of which process need not be here explained as the method is well understood by those skilled in the molding art. The special advantages of using slag are its density and its abundance and cheap cost. 20 In fact, the cost of slag may be regarded as negligible as it is regarded generally as a waste product having no established utility whatever.

The method of manufacturing, merchandizing and using the device herein shown and described is as follows:—The blocks may be molded in the vicinity of a steel mill or other source of slag. The sheet metal frames 12 may be manufactured at a factory specializing in sheet metal punchings. 25 The pulleys are preferably formed by spot-welding two press-formed sheet metal punchings together as at 8', or cast pulleys may be used. The pulleys may be made 30 wherever convenient, and the cords will, of course, come from some other source. The several parts if desired may be finished and stored in the vicinity of the point of manufacture and may then be shipped directly 35 to the point of ultimate consumption or use whenever required for filling orders and for this purpose may be shipped directly to the building where they are to be used. The parts may then be assembled and the finished product may be fabricated at the immediate point of installation by unskilled 40 hands. A great advantage of this method of shipping the parts separately and assembling at the point of installation is that 45 the several parts may be shipped in bulk according to their own respective freight rates, that is to say, the weights or blocks may be shipped as bricks, and the other parts according to their own characters respectively. The expense of shipping the 50 goods is thus much less than would be required if the device were assembled before shipment, in which case a high freight rate would apply, owing to the classification then 55 being for a manufactured product rather than for mere materials. Another point of advantage in molding the bricks separately and providing interchangeable rods 10 and frames 12 is that rusting of metal parts is 60 avoided for if said parts were molded into 65

or joined to the bricks when the latter were molded, the metal would be subjected to moisture for a considerable period with the result that rusting would occur and a corresponding deterioration in quality and appearance. As it is absolutely necessary for the "curing" or hardening process to keep the concrete weights wet from two to seven days, either by the use of steam or water, the advantage of the concrete weight being 70 separate from the pulley device during this period can be readily seen. The bricks are preferably "steam cured" for 35 to 48 hours, and then "yarded" till needed to fill orders. 75

It is to be understood that the bricks may 80 be molded in various lengths, and that a standard full sized weight unit measuring 2" x 4" x 8" and weighing about eight pounds may be supplemented with one or more two pound quarter size units each 85 measuring 2" x 4" x 2". This assures great flexibility and convenience, as well as low cost. Special needs may be instantly met by supplying the appropriate parts and fabricating the attachment accordingly, no tools 90 being necessary excepting to bend the pulley frame punching 17 into shape, and the parts all being secured by the cotter pins 11, 13 and 14.

In making these weights I prefer to use 95 one part of Portland cement with four or five parts of slag crushed to pass through a screen of $\frac{1}{2}$ " mesh, mixed with sufficient water (10 to 15%) to make a good working concrete adapted for ready molding. I prefer to mix with this concrete about one third part by weight of coarse slag ranging upward to about $\frac{1}{4}$ " to $\frac{1}{2}$ " in size. The aggregate contains slag particles ranging in size 100 all the way down to small grains or dust. 105

In the manufacturing of concrete weights, using a power brick machine, (with perforating device), seven men can produce 10,000 weights per day, 9 hours labor. An important advantage in the use of a power 110 machine, is that 40 tons pressure may be developed insuring a denser brick compared with weights produced in the ordinary ways. They are true and uniform, and the core aperture is adapted to receive a flat stringing-rod in non-turning relation. Moreover, 115 this method produces a weight of uniform density, and a weight which is smooth and can be handled with a minimum chance of breakage. 120

The pulley frames or casings 12 may be stored and shipped flat and then bent into shape after shipment, at the point of use.

In shipping, the concrete blocks pass as 125 "common brick", the pulley attachments as "sash pulleys", and the other materials accordingly, so that minimum rates apply. Packing expense is reduced to a minimum and is largely eliminated.

Although but one complete specific em- 130

bodiment of this invention is herein shown and described it is to be understood that some of the details of the construction shown may be altered or omitted without departing from the spirit of this invention as defined by the following claims.

I claim:

1. A sash weight comprising a dense concrete block having an axial perforation, a supporting member extending through said

secured to said member, and means adapted for detachably connecting said pulley to said member.

2. A sash weight hanger comprising a pulley wheel, a sheet-metal frame wherein said wheel is mounted and a rod having one end detachably secured to the lower part of said frame.

Signed at Chicago this 4th day of April, 1921.

CHARLES NATHAN JOHNSON.
